UNITED STATES PATENT OFFICE

2,548,597

SIRUP AGITATOR FOR LIQUID DISPENSING DEVICES

Samuel H. Ellison, Riverside, Ill., assignor to True-Ade, Inc., Chicago, Ill., a corporation of California

Application April 23, 1945, Serial No. 589,883

7 Claims. (Cl. 259—95)

1

The present invention relates to liquid dispensing devices and especially to a novel cup vending machine for dispensing liquid refreshments in which the parts are so constructed and arranged as to be readily removable for replacement or assembly. In addition, all parts in contact or associated with the dispensing of the syrup are preferably of polished stainless steel or the like and refrigerated at all times the machine is operating. Furthermore, there are no springs, gaskets or packing employed in any parts associated with the measuring or dispensing of the syrup, so that these parts may be readily sterilized to assure maximum sanitation.

Another feature of the present invention is to provide a mechanism comprising simplified construction and requiring a minimum number of operating parts to thereby greatly reduce the cost and necessity for subsequent servicing. All mechanical movements employed are simple in construction and design and positive in operation.

The invention further comprehends a novel means and mechanism for periodically agitating the syrup to prevent the settling of any contained pulp or solids. Although the present invention is preferably concerned with the dispensing of natural fruit drinks containing natural fruit pulp, it is to be understood that it is not limited thereto, especially as such agitation carries the cooled syrup from the syrup well which is refrigerated upwardly through the contents of the bottle where it mixes with the warmer syrup and thus facilitates cooling of the entire contents of the bottle.

Further objects are to provide a construction of maximum efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a view in front elevation of the novel dispensing device and showing in dotted outline the relationship of the parts.

Figure 2 is a view in end elevation thereof.

Figure 3 is a top plan view.

Figure 4 is an enlarged fragmentary view part in vertical cross section and part in elevation

2

taken on the line 4—4 of Figure 3 and showing the syrup bottle and associated parts.

Figure 5 is a fragmentary enlarged view in vertical cross section showing the manner of agitating the contents of the syrup bottle.

Figure 6 is a view in horizontal cross section taken on the line 6—6 of Figure 5.

Referring more particularly to the drawings and to the novel embodiment therein selected to illustrate the invention, the dispensing device comprises a cabinet 1 having a dispensing opening 2 which is preferably closed by a sliding, transparent panel 3 adapted to be lifted by the purchaser when the cup 4 is properly filled with the dispensed beverage from the dispensing spout 5.

In the base of the cabinet is a refrigerating unit 6 and a water filter 7 shown in dotted outline in Figures 1 and 2 but which form no part of the present invention and are therefore not shown in detail. The cabinet is suitably insulated about the syrup bottle 8, syrup well 9 and the water tank 10 from which water or other suitable diluent is pumped to a delivery pipe 11 having a gooseneck 12 adapted to discharge a measured quantity of water into the dispensing spout 5. A suitable solenoid water valve 11 (Fig. 4) controls the flow whereby a measured quantity of water is delivered to the tank 10 and in turn to the dispensing spout 5. A measured quantity of syrup is also discharged into this dispensing or delivery spout from a measuring cup 13, it being understood that in the passage of the water and syrup through the dispensing spout 5 and the curved portion 14 thereof and the manner in which the discharged liquid is ejected into the cup 4, causes an intimate mixing of the syrup and water when discharged into the cup 4.

As shown more clearly in Figure 4 a relatively heavy wall of insulation encompasses the syrup bottle 8, syrup well 9 and the water tank 10, the syrup well and water tank being provided with a series of cooling coils 15 carrying the refrigerating fluid to maintain the water and syrup at the desired low temperature. As the mechanism is especially adapted for dispensing a fruit drink containing pulp residue or suspended solids, the invention comprehends agitating this syrup at least intermittently or at suitable intervals. This is preferably accomplished by means of a nozzle 16 which is telescoped and freely slidable in a sleeve 17 formed or provided on the upper surface of a housing 18, the sleeve having a reduced neck 19 and the nozzle having a flange 20 limiting its upward movement. This telescoping of the

nozzle 16 within the sleeve 17 when not in operation, permits quick and easy removal of an empty bottle and replacement by a full bottle of syrup.

The nozzle and its encompassing sleeve or collar are preferably disposed at a slight angle with the vertical so that syrup from the well 9 is drawn through the opening 21 in the base of the housing 18 by the vaned agitator or impeller 22 and is propelled through the tangential passageway 23 in the housing and then forced upwardly through the opening 24 in this nozzle to be ejected under pressure adjacent the interior surface of the neck 25 of the syrup bottle. By thus locating the nozzle and disposing it at an angle, considerable agitation is given to the contents of the syrup bottle. This not only prevents the pulp from settling but also uniformly cools the contents of the bottle.

The impeller 22 is disposed at the lower end of a drive shaft 25 driven from a motor or other prime mover 27. Although I prefer the agitation to be intermittent and at stated intervals, it is to be understood that such agitation may be continuous, if desired. As the nozzle 16 is loosely telescoped within the sleeve 17 and forced upwardly by the pressure and circulation of the agitated syrup when the impeller is operating, to prevent it from seating upon the base 28 of the housing 18 when the impeller stops and the nozzle drops by gravity, an abutment 29 such as a screw or the like may be provided to intercept the drop of the nozzle. This spaces the lower end sufficiently above the base to permit the liquid when impelled, to pass under the nozzle and raise it by the pressure of the liquid stream to the position shown in Figure 5.

Syrup from the bottle is fed by gravity into the well 9 and the syrup from this well flows into the measuring cup 13. This measuring cup is slideable upon the upper end of the dispensing spout 5. To assure complete flushing of the spout 5 of the dispensed syrup and to facilitate mixing, the water discharged from the pipe or nozzle 12 is preferably given a swirling action. This may be accomplished by means of a spiral insert 91 disposed in the end of the nozzle.

From the above disclosure it will be apparent that the invention comprehends a novel and simplified agitating means whereby the syrup is so agitated as to prevent settling of any pulp or solid matter and to effect uniform cooling.

Having thus disclosed my invention, I claim:

1. In a liquid dispensing device for dispensing drinks including syrup of natural fruit drinks containing pulp or solids, a container for the syrup disposed in inverted position and means for agitating the syrup in the container, said means including a nozzle disposed adjacent the open end of the container for projecting a stream of the syrup into the contents of the container.

2. In a liquid dispensing device for dispensing drinks containing natural fruit syrup having suspended solid matter, a container for the syrup disposed in inverted position and having a restricted outlet, and means for agitating the contents of the container to prevent settling of the contained solids and including a nozzle at the restricted outlet for projecting a stream of the syrup into the container.

3. In a liquid dispensing device for dispensing drinks containing suspended solid matter, a container for the syrup, a well for receiving syrup from the container, and means in the well for

circulating the syrup including a nozzle discharging a stream of syrup from the well into the container to maintain the solid matter therein in suspension.

5. In a liquid dispensing device for dispensing drinks containing suspended solid matter, a container for the syrup, a well into which the syrup flows from the container, means for cooling the syrup in the well, and agitating means in the well for circulating cooled syrup therein and projecting a stream of syrup from the well into the contents of the container to thereby agitate the syrup therein and maintain the solid matter in suspension.

15. 6. In a liquid dispensing device for dispensing a drink comprising a syrup of natural fruit including pulp or other solid matter and a diluent, a container for the syrup and a well receiving a predetermined depth of syrup from the container and in which the syrup is cooled by refrigeration, means for circulating cooled syrup in the well and means for projecting a stream of syrup from the well through the contents in the container for agitating the contents therein to thereby 20 maintain the solid matter in suspension and simultaneously cooling the contents.

25. 7. Circulating mechanism for liquid dispensing devices in which syrup from a storage container feeds into a well from which it is dispensed, comprising agitating means within the well and means associated with the agitating means for projecting a stream of syrup from the well into the storage container in such manner as to agitate the syrup in the container and maintain 35 any solid particles therein in suspension.

30. 8. Mechanism for agitating syrup contained within a bottle or other container supplied to a cup vending machine for dispensing liquid refreshments, comprising a receptacle into which 40 the syrup flows from the container, a housing in the receptacle and provided with an agitator adapted to circulate syrup under pressure from the receptacle to the container, and a telescoping nozzle in the housing for receiving the syrup 45 under pressure and discharging it into the container in such manner as to cause thorough agitation of the contents of the container, said nozzle being telescopically mounted in the housing in such manner as to project into the neck 50 of the container when the agitator is operating and drop therebelow when it is not operating to permit removal and replacement of the container.
